UNITED STATES PATENT OFFICE.

WILLIAM NICHOLS, OF LOS ANGELES, CALIFORNIA.

TIME-TABLE MECHANISM.

1,182,303

Specification of Letters Patent.

Patented May 9, 1916.

Application filed September 6, 1910. Serial No. 580,690.

To all whom it may concern:

Be it known that I, WILLIAM NICHOLS, a citizen of the United States, residing at Los Angeles, in the county of Los Angeles and State of California, have invented certain new and useful Improvements in Time-Table Mechanisms, of which the following is a specification.

This invention relates to improvements 10 in time table apparatus and it has for an object, among other things, the production of a mechanism by which time tables and particularly those of railroads may be compared and examined.

15 It is a further object of the invention to supply mechanism by which old or existing time tables and new time tables may be compared, the relation of all their parts being examined and their bearing one upon 20 another, being determined, the conditions resulting from a change from one time table to another, being also developed so that they can be made clearly apparent and noted.

Another object of the invention is the 25 provision of a mechanism in which part or the whole of a time table may be temporarily covered so as to hide from view such parts of one or more of the tables, that may become inoperative for any reason, as for 30 instance a change from an old schedule to a new.

It is also a further purpose of the invention to provide a time table mechanism in which the tables examined may be illuminated, either by natural or artificial means, and may thus be used to advantage by day 35 or by night.

With these and other objects in view the invention consists in certain novel constructions, combinations and arrangements of parts, as will be hereinafter more fully described and claimed.

In the accompanying drawings, forming a part of this specification:—Figure 1 is a 40 front elevation of the improved time table mechanism, portions thereof being broken away to show some of the interior construction of the apparatus. Fig. 2 is a horizontal transverse sectional view taken through the 45 mechanism upon the line *a*—*b* of Fig. 1. Fig. 3, is a perspective view showing the interior of the time table mechanism, the back wall thereof being removed to reveal the same. Fig. 4, a vertical cross sectional view taken through the apparatus upon the 50 line *c*—*d* of Fig. 3. Fig. 5, is a fragment-

tary view of a portion of one of the curtains employed for covering a part of the apparatus. Fig. 6, is a detail sectional view of a portion of said curtain and a part of the front of the time table mechanism, showing the means employed for holding a curtain in an adjusted position. Figs. 7 and 60 8, are detail views in front and side elevation respectively, illustrating an adjustable 65 station indicator or pointer employed upon the front of the apparatus. Fig. 9, is a front elevation of a modified form of the time table mechanism, in which a single line of stations is used for both time tables that 70 may be compared. Fig. 10, is a vertical central section through the same. Figs. 11, 12, 13 and 14, are diagrammatical views, showing schedules as they are sometimes used with the station, time, direction, class, 75 and number designations on one sheet, the schedules being held side by side, and illustrating the use of curtains of different sizes and shapes, for covering portions of the 80 said schedules and thus indicating the effective parts of the same on the days of change of time table.

The present invention is particularly useful in connection with railroads, making it possible to demonstrate in concrete form 85 the relations of time tables to each other, and the effect upon old and new schedules resulting from a change of time tables at given times. The accurate working out of 90 time table changes is so intimately connected with the safety of the traveling public, that it has become necessary for railroads and railroad associations, to develop certain rules governing the operation of trains and the bearing upon old and new schedules, of 95 a change to a new one, that it has become an important matter that all employees be carefully schooled in these things.

The time table apparatus forming the subject matter of the present invention is 100 designed for this purpose, and is well adapted to illustrate by means of the related parts of the device, the consequences of making time table changes, under the rules of the railroad companies. Not only can 105 the new and old time tables be compared side by side, but the effective parts thereof can be ascertained and their relation to one another be determined.

The construction of the mechanism is 110 such, that one or more schedules may be brought opposite each other so that the num-

ber, class, day or days of leaving a given station, the direction of trains operable on the schedule and the initial and terminal stations can be compared at a glance, and the time when the new schedule goes into effect can be shown together with its effect upon the trains of both schedules.

The principal features of each schedule may be carried on a single strip or sheet of material as shown in Figs. 11, 12, 13 and 14, and the said schedules in this form may be hung or placed side by side, for comparison, but the invention is generally embodied in mechanism like that illustrated in Figs. 1, 2, 3 and 4 and the said invention will now be more fully described, reference being had to said figures. As shown in the drawings, the time table apparatus comprises a casing, housing or closure 1, the front wall of which is provided with a number of apertures through which the schedules may be made apparent. Within the housing 1 and to the rear of the perforated front are mounted a schedule time strip or scroll 2, one or more station strips or scrolls as 3, a strip or scroll capable of showing the class, number and frequency of the schedule as at 4, as well as other strips or scrolls as 5, indicating the numbers of the time tables.

The scroll strip 2 is made up of a strip or band of flexible material, preferably of a semi-transparent or translucent character, as for instance tracing linen or some similar material, which will permit light to shine through from the rear or interior of the apparatus and yet not reveal the inner structure of the housing 1. The said strip or band of material 2, is made of ample length to contain or have marked, painted, printed or otherwise placed on the face thereof, columns of indications, showing the times when trains are due and authorized at various stations. The scroll strip 2 is wound upon vertical rollers 6, 6, which are arranged within the housing 1, preferably in the front corners thereof as shown in Figs. 1 and 2. The journals of the rollers 6, 6, have bearings as at 7 and 8 in the structure of the housing. One of the journals of each roller 6, preferably the lower one is extended beyond its bearing and carries a beveled gear 9, which meshes with an actuating pinion 10, carried by and actuated by an operating shaft 11. Each shaft 11 projects through the front wall of the housing 1 and is provided with a crank 12, by which it may be turned. By turning one crank 12, the scroll strip 2 is caused to travel transversely in the apparatus behind the perforated front, it being wound up on the roller 6 thus actuated and unwound from the other roller to a corresponding degree. The operation is reversed of course by turning the other roller 6 when the scroll strip is to be made to travel in the opposite direction. The said scroll strip 2

is provided with spaced columns of time indications, as 13 and 14, which are adapted to be stopped opposite apertures or openings 15 and 16, in the front wall of the housing 1. The openings 15 and 16 are arranged in horizontal alinement with apertures or openings 17 and 18 through which appear the names of the stations passed by the trains operated over the schedules. These stations have been indicated for convenience by the letters of the alphabet from A, to H as shown in the drawings, each of said letters indicating a station. These station indications are carried by translucent material like that of the scroll strip 2 and may be fixed or movably arranged as preferred behind the openings 17 and 18. The said station indications are generally carried however by vertically moving scroll strips, as 3, 3, which are wound upon upper rollers 19 and 20 and lower rollers 21 and 22. In this way schedules over different divisions of a road, or over subdivisions thereof may be shown and examined, and changes in routes may be displayed. Each of said rollers 19, 20, 21 and 22 is connected by intermeshing beveled gearing with a crank shaft the crank portion of which extends outside the housing, the said crank shafts being designated respectively by the numerals 23, 24, 25 and 26, by which the station strips 3, 3, may be rolled and unrolled and caused to travel up and down, to bring the desired stations into view through the openings 17 and 18. The station strips 3 are arranged to move in front of the transverse time strip 2 so that they will not be hid by said time strip. The arrangement is such that the time strip can be adjusted for bringing new columns of time indications into view to one side of the station indications, without affecting the station strips. The station strips can also be adjusted irrespective of the time strip.

The columns of time indications upon the strip 2 are preferably arranged in pairs, each pair being made up of one column giving the time indications for the various stations on the old schedule and the other column giving the time indications for the new schedule. The spaces between the said columns come behind the station strips 3 and do not therefore interfere with them in any way, nor do the said station strips 3, cover any indications or data upon the time scroll or strip 2.

Just above the time strip 2 is arranged a similar strip 4, which may be termed the class or day strip. This strip 4 is arranged to move transversely of the housing 1, behind openings 28 and 29 in the front thereof and passes around rollers 30 and 31, arranged in the opposite front corners of the said housing 1, above the rollers 6, 6. A transverse bar 32 mounted in the housing, carries the journal bearings 7, of the rollers

6, and also supports bearing brackets 33 which engage and movably support the lower ends of the idlers 30 and 31. The upper ends of the said idlers are journaled 5 in similar brackets 34 secured to the side walls of the housing 1. The ends as at 27 of the said strip 4, are wound upon rollers 35 and 36, which are journaled in suitable brackets as 47, 47, and 48, 48 or other suitable supports arranged in the rear part of the housing near the opposite corners thereof, as clearly shown in Figs. 2 and 3. The strip 4 is formed of translucent material, so that words, numbers or other indications of an opaque character, printed, painted or otherwise placed thereon, will show forth in strong relief when natural or artificial light is permitted to shine through the front openings of the housing 1, from the rear or interior thereof. The front surface of the said strip 4, is provided with columns in multiple, preferably in pairs, the said columns usually indicating as shown in Fig. 1, of the drawing, the class, the number of the schedule and the day or days upon which the trains of the schedules compared are run. Actuating shafts 37 and 38 extend from the front of the housing 1, back to the lower ends of the rollers 35 and 36, they being connected with the said rollers by beveled gearing as at 39 and 40. The said shafts 37 and 38 are provided with cranks 41 and 42 outside the housing by which they may be turned. By the operation of these cranks 35 the strip 4 can be moved back and forth in the housing 1, to bring different columns of indications thereon, showing the class, train or schedule number, and days of running the trains, opposite the openings 28 and 29 40 in the front of the housing. To one side of these openings 28 and 29 are larger openings 43 and 44, in which are made to appear the time table numbers, and below these are smaller openings 45 and 46 in which the words, "Stations", are usually arranged to appear, referring to the columns of station names below which are seen through the openings 17 and 18. The designations appearing in the openings 43, 44, 45 and 46 45 may be mounted on semi-transparent or translucent material so that the light may shine through them as in the case of the strips 2 and 4, already described and said material may be fixed in position behind said openings, but is generally made movable, the material being in the form of traveling strips or bands 5, 5, which are wound around upper rollers 49 and 50 and lower rollers 51 and 52. These strips 5, 5, are 50 quite similar to the station strips heretofore described and their rollers are each capable of actuation by means of crank shafts and intermeshing beveled gears as at 53, 54, 55 and 56, the crank portions of said shafts 55 being arranged outside the housing. These

time table number strips 5, 5, extend in front of and across the transversely arranged class strip 4.

Above the class strips and the time table strips, elongated openings 57 and 58 are arranged in the front of the housing 1 and behind these openings and inside the housing is journaled a rocking member 59, the said rocking member extending transversely of the housing and being journaled therein 75 at 60 and 61. The rocking member is preferably formed with two flat faces, as 62 and 63 upon which words indicating the direction of the schedule or train are mounted, upon translucent material. The ends of the 80 rocking members preferably extend at right angles to the faces 62 and 63 and support them upon the journals at 60 and 61. An actuating arm or lever 64 is secured to one end of the rocking member and a draw bar 85 65, pivoted thereto, extends outwardly through an opening in the front wall of the housing 1 where it is provided with a handle 66. Notches as at 67 in said bar 65 are adapted to engage the front of the housing 90 in such a way as to lock the rocking member in its adjusted positions. By operating the rod 65 the rocking member may be so moved as to bring different direction indications, as for instance, "Eastward", or "Westward", 95 etc., opposite the elongated openings 57 and 58.

Above the elongated openings 57 and 58 are similar elongated openings 68 and 69 behind which a rocking member 70, like the 100 rocking member 59 just described, is journaled in the housing, its flat faces 71, 72, carrying indications which show whether the time tables are old or new. The words "Old", or "New", are mounted upon translucent material so that light shining through from the interior of the housing, will bring out the said words in bold relief. The rocking member 70, is provided with an arm 73 and an operating bar 74 in all respects like 105 the bar 65 and the arm 64 already described. The said bar 74 is likewise provided with locking notches 75 and a handle 76. The rocking members 70 can thus be rocked back and forth to bring its flat faces with their 110 115 indications, opposite the elongated openings 68 and 69.

Above the openings 68 and 69, are elongated openings 77 and 78, in one of which the words "New time table effective", is generally made to appear, while in the other, the time when the new time table is effective is indicated. In both instances the words and indications are placed preferably upon translucent material, so that light shining 120 through it from the back, brings out the said words and indications in bold relief. In the case of the material at the opening 77, it is usually fixed in position there being no need ordinarily for making it movable. As 125 130

the time when a schedule becomes effective, is changed from time to time, the material opposite the opening 78 is preferably made in the form of a strip or scroll band, carrying as many time indications as desired, the said strip being rolled upon rollers 79 and 80, mounted inside the housing 1. Actuating shafts 81 and 82, carrying cranks 83 and 84 are connected with said rollers, by 10 inter-meshing beveled gearing, whereby the strip of material may be adjusted with respect to the opening 78, in the giving the time when the schedule goes into effect.

It will be observed that by the arrangement of transversely and vertically moving strips, operable in a given relation to each other, old and new schedules, or different divisions of the same schedule, may be brought in such relation to each other as to 15 compare all the features of one with those of the other. Also a change in one may be made to show results brought about thereby, said results affecting one or both of said time tables.

Under the existing rules of the railroads, an old schedule is often effective for a part of its time or until a train run thereon reaches a given station, and frequently a train that is able to run part way upon an 20 old schedule, may be able to assume a part of the new schedule, after the new schedule becomes effective and thus complete its run according to such new schedule. In order to assist the eye in following the movements of trains under these and other conditions, the apparatus embodying the invention, is provided at suitable points upon its front face with movable indicators as 25 85 and 86. These indicators are arranged to 30 move or be adjusted upon bars or rods 87 and 88, preferably fastened on the housing 1, in vertical positions between the stations indicated on the station strips, and the time periods indicated on the time strips, as 35 clearly indicated on Fig. 1. As shown in the detail views Figs. 7 and 8, each of these indicators preferably consists of a short sleeve 89, capable of sliding on its supporting bar or rod and a clamping or thumb 40 screw 90, by which it can be set and held 45 opposite any station desired. An arrow or suitably shaped pointer 91, is carried by each sleeve and clamp screw. Thus when a 50 train is authorized to run on the old schedule to a certain station, that station can be 55 shown upon the apparatus by moving the indicator or pointer 85, to a point on the rod 87 opposite said station. If the train can also assume the time of the new schedule 60 at a given station that station can be indicated to the eye by bringing the pointer 86 to a position upon the rod 88 opposite said station. This arrangement is found in 65 practice to very materially aid the time table student in mastering the actions of trains

that are able to run upon old and new schedules before and after the time of change from one to the other.

As a further helpful aid in demonstrating and teaching the relations of new and old 70 schedules or different parts of the same schedules over different divisions or subdivisions of a railroad and the actions of trains operated upon such schedules it is found advantageous to be able to adjustably cover a 75 part or parts or the whole of a schedule or schedules. For this purpose the apparatus is provided at suitable points with curtains which can be drawn out over certain parts of the front of the housing. Any number 80 of curtains of the same or of different widths or shapes may be employed as found desirable within the spirit of the invention. In the illustration herewith a plurality of such curtains are shown mounted at both 85 the top and bottom of the apparatus. Thus curtains as 92, 93 and 94 may be mounted in brackets 95^a and 96^a at the top of the housing 1. These curtains are carried by spring 90 actuated rollers, preferably of the type generally used for window shades and in order to bring them quite close to the front surface of the housing 1, they are made to pass respectively behind idlers 95, 96 and 97 which are also journaled in the brackets 95^a 95 and 96^a. Any one of the said curtains may thus be drawn so as to cover all or a portion of the front of the housing 1. As before intimated the curtains may be effectively 100 made of different shapes, thus as shown in Fig. 11 curtain 92 may be made of the full width of the front of the schedule indicated on the front of the apparatus. Curtain 93 may be made quite narrow so as to cover only a part of one schedule, while curtain 94 may be made for a part of its length of a width equal to part of the time indications and for the remainder of its length of a greater width so as to cover all of the time 105 indications.

It is also found useful to employ a plurality of curtains at the bottom of the housing there being shown in Figs. 1 and 4 of the drawing, three curtains as at 98, 99 and 100. These curtains are like those at the top mounted on proper spring actuated rollers of the self acting type and are directed in close proximity to the face of the housing by guide rollers or idlers 101, 102 and 103, 110 all of said curtain rollers and idlers being 115 journaled in brackets 104 and 105 secured to the housing 1. These curtains are made to cover all or part of the schedules by drawing them upwardly to the proper heights. The lower curtains like the upper ones may be made of varying widths and shapes. Thus for example curtain 98 may be made wide enough to cover both schedule columns. Curtain 99 is preferably narrower so as to 120 cover only one schedule column while curtain 125 130

tain 100 is made wide enough for a part of its length to cover the time indications of one schedule but narrower for the remainder of its length for covering only a portion of 5 said time indications.

- All of the curtains are provided with fasteners on their outer edges which are preferably in the shape of rings or eyes as 106 which are capable of engaging projections 10 or detents arranged on the front wall of the housing 1. The detents for holding the upper curtains are preferably downwardly inclined pins 107 mounted at suitable intervals in the material of the housing's front wall. 15 Similar upwardly projecting pins or detents 108 are mounted on the front of the housing to secure the lower curtains. These detents are generally arranged opposite each of the stations indicated on the station strips. 20 The full width curtains as 92 and 98 are useful in covering the entire width of a schedule to a given station so as to indicate how far a train is authorized to travel upon the old schedule and when it may assume 25 and move upon the time of the new schedule. Thus as shown in Fig. 11 curtain 98 which covers the lower part of the old schedule shows that train No. 1 is authorized to move as far as station D on the old schedule before 30 the change of time table becomes effective, say at 12.01 A. M. At the same time curtain 92 may be set to cover the new time table to station D to indicate that the train may wait for the new time at D and assume 35 the time of the new schedule for the remainder of its run. Of course it will be understood that either curtain may be pulled to cover its entire schedule when either the old or the new schedule is rendered entirely 40 ineffective upon the day of the change of time table.
- The curtains 99 and 93 are useful when the trains are run in sections, the said curtains being of such a width as to cover the 45 second half and first half respectively of the old and new time tables and by this means as shown in Fig. 12 when a train is run in two sections and the first section completed its run for the day, before the new time table 50 became effective, it is authorized to run upon the old schedule. The second section, however, may not have left the initial station A before the new time table went into effect in which case as indicated by the curtain 93 55 which leaves the second half of the new schedule uncovered, the second section of the train can assume the time of the new schedule throughout its run on the day of the change of the time table.
- 60 The curtains 100 and 94, are used to designate the runs of trains operated in sections where one of said sections may be able to make its entire run on one of the schedules whereas another section must make its run 65 partially on the old schedule and partially

on the new. Thus as shown in Fig. 13 the upper narrow portion of the curtain 109 is set to cover one half the time spaces opposite stations F, G and H leaving uncovered the other half of the spaces opposite F, G 70 and H and all of the spaces opposite stations A, B, C, D and E, thus indicating that the first section of train No. 11 (it being operated in two sections) can make its complete run on the old time table before the 75 change to the new is effected and the second section may run upon the old schedule until it reaches station E. The curtain 94 is set so that its widest portion covers the full width of the time spaces opposite stations 80 A, B, C, and D, while its narrower end projection 110 covers half of the time spaces at E, F, G and H. In this simple manner it will be made plain that the first section of the train which fulfilled the schedule on the old 85 time table cannot run on the day of change, on the new time table and the second section which has fulfilled its run on that day, on the old time table as far as station E, can only operate on the new time table for the 90 remainder of its run, that is to say, from station E to station H.

The curtains of the shape of 94 and 100 are also useful in showing the operation of a train running in three sections. Thus as 95 shown in Fig. 14, the first section can make its entire run on the old schedule and does not operate upon the new at all. The second section runs upon the old schedule from A to E and on the new schedule from E to H, 100 while the third section does not run upon the old at all, but assumes the time of the new schedule and runs thereon from A to H. It will thus be evident that the curtains described are capable of various adjustments 105 to show the effective portions of schedules under varying conditions and relations as existing between the schedules and the trains run thereon, whether in sections or as a single train. The curtains thus coöperate with 110 the time strips and the station strips in demonstrating the different train relations developed by the use of certain schedules and the change from one to another at given times.

115 While it is important that the time, station and other scrolls or strips used in the device be made of translucent material, the curtains are preferably more opaque and can be made of material which will intercept a 120 part or all of the light that ordinarily passes through the said scroll strips. In practice it is found very convenient to employ colored curtains and they are generally made of a red color so as to be easily distinguishable 125 from other parts of the mechanism.

The indicators or pointers 85 and 86 may also be used in connection with the curtains to point to stations where a train stops using one schedule or begins upon another and the 130

arrows of said indicators may if desired be turned to show the direction in which a train is moving. The said indicators 85 and 86 are also useful in showing the action of 5 an opposing train, that is to say, a train running over the same line in an opposite direction to the train of the schedule examined. The said pointers may be set to show where the opposing trains should meet 10 or may be used to indicate the position occupied by the opposing train with relation to the schedule under consideration at the time of change of time table. It will thus be evident that the parts of the mechanism 15 are admirably adapted for working out and demonstrating in a form easily understood by the employees of a railroad or others, all the different combinations of circumstances and positions developed in the running of 20 trains according to authorizing schedules, put forth under the rules of railroad associations generally.

While natural light may be admitted through the back of the apparatus to illuminate 25 the different indicating strips or scrolls and other surfaces, upon which the letters, words and numerals, of an opaque character are affixed, so as to show said characters in bold relief, the housing is also provided with 30 artificial light producing means interiorly arranged. Thus electric lights at one or more points as 111 may be arranged within the housing 1. A gas burner as 112 may also be arranged in the housing for use where 35 electric lights cannot be operated. The inner surface of the back of the housing may be provided with any highly polished surface to afford a reflecting means behind the lights. By the use of the artificial lights the 40 mechanism is rendered as useful at night as in the day time.

While the mechanism is preferably constructed with two station strips and a set of 45 openings is provided for each as heretofore described, a single station strip and openings therefor may also be used in connection with the time strip, within the spirit of the invention. Such an embodiment of the invention has been illustrated in Figs. 9 and 50 10 of the drawings. As shown in these views, the housing 113 is provided with a central set of openings as at 114 through which are made to appear the names or indications for the stations of the schedules, to 55 be compared. On the right and left of the column of stations are columns of openings 115 and 116 for the time indications showing when trains are due at the different stations on the schedules. The time indications 60 are carried by a transversely moving strip or band 117 which like the strip 2 above described carries columns of time indications in pairs so located as to register with columns of openings 115 and 116 and 65 the said strip is rolled up at its ends upon

rollers 118 and 118^a. Crank shafts 119 and 120 project from the said rollers to points outside the housing 1, so that by operating the crank portions thereof the strip 117 may be made to move back and forth behind the 7⁷ openings 115 and 116 so that the desired time indications may be caused to show through them.

A station strip 121 carries the names or 75 indications, as the letters of the alphabet as A to H, for the stations of the road and is arranged to move vertically in front of the strip 117 and behind the openings 114. The ends of the strip 121 are wound upon actuating rollers 122 and 123, which are provided with the usual crank means extending outside the casing as at 124 and 125. The said strip 121 also passes over an idler roller 126 to prevent its engaging the upper edge of the time strip 117. It will be apparent 80 that by this structure one set of station names or strips carrying the same may be used for a plurality of time schedules. Traveling indicators as 127 and 127^a are also provided on the front of the housing for 85 indicating how far a schedule may be operable on the day of the change of a schedule. These indicators or pointers are movably mounted on the rods 128 and are preferably similar to the indicators or 90 pointers 85 and 86 heretofore described.

Above the time strip 117 is another strip or scroll band as 129 mounted upon actuating rollers 130 and passing around idlers 131 inside the front of the housing. The 160 rollers 130 are provided with operating crank shafts 132 which extend outside the housing 113 at the bottom. The said strip 129 passes behind openings 133 and 134 in the front of the housing and arranged above 165 the time openings 115 and 116. This strip 129 is provided upon its front face with columns of indications designating whether the schedule is old or new and giving the 170 class and the number of the train or schedule 116 and whether the train is a daily or not. These designations or words are arranged in multiple columns on the strip 129 so that old and new schedules may be compound 175 with each other. Passing in front of the central portion of the strip 129 is a vertically 180 movable strip 135 which is adapted to be wound upon upper and lower rollers 136 and 137 respectively. The said rollers are provided with actuating cranks 138 and 139 120 which extend outside the housing. The said strip 135 carries designations and words telling when the new time table is effective giving the hour and the day and these designations are spaced so as to come behind and 125 register with a column of openings in the front of the housing as at 140, the said column, preferably occupying the space between the columns of openings 133 and 134.

The modified form of the mechanism as 120

illustrated in Figs. 9 and 10 is also provided with curtains as 141 at the top of the housing and bottom curtains as 142 which are in all respect similar to the curtains 5 92, 93, 94, 98, 99 and 100 as already described with respect to the preferred form of apparatus and like them are adapted to be drawn over portions of the face of the housing to cover ineffective parts of the 10 schedules at the time of the change of time table. Defents 143 and 144 are also provided on the front of the housing for holding the curtains in adjusted positions. Such an apparatus may have an opening at the 15 back as at 146 and may be provided with electric lights 147 and a gas burner 148 so that the interior of the housing may be illuminated by either natural or artificial light. The various strips described are all 20 preferably made of translucent material as for instance tracing linen upon which the words, letters, indications and other configurations are placed, they being of an opaque character. The comparisons of schedules 25 and the working out of results due to changes of time tables can all be set forth in a clear and concrete form with the modified form of the apparatus, all being within the spirit of the invention.

30 It will be observed that either form of the apparatus described is admirably adapted for the exhibiting of the essential features of one or more time tables and that where more than one time table is brought to view 35 its relation and arrangement with respect to another time table which may also be shown, can be positively demonstrated to the eye of persons working out the changes or comparisons of time tables, or to students being instructed in the rules and conditions affecting such time tables.

While a semi-transparent or translucent substance as tracing linen has been described as preferably used for the scroll and other 40 strips, employed in the mechanism, it should be clearly understood that any translucent material may be used without departing from the spirit of the invention.

In fact any material which will set forth 45 the characters printed or otherwise produced upon its surface may be employed within the scope of the invention.

All mechanical equivalents of the details of structure shown and described are of 50 course also embraced in the spirit and scope of the present invention.

As intimated at the beginning of the specification, the broad idea of the invention 55 includes the comparison of schedules, whether they be each in one piece as shown in Figs. 11, 12, 13 and 14, or in several sections as shown in the other views of the drawings, and the covering of portions or 60 of all the schedules in showing their effectiveness. The curtains employed may also

be arranged at any suitable points for covering the said schedules, and are not necessarily mounted at the extreme top and bottom of the housing, to be brought within the spirit of the invention.

Having now described my invention what I claim as new and desire to secure by Letters Patent, is:--

1. A time table mechanism having a principal time strip provided with a plurality 75 of time indications forming schedule columns extending transversely of the strip, the said strip having blank spaces between the said columns, and a plurality of station strips arranged to extend across the time 80 strip in parallel relation to each other, and separated sufficiently to register with the said blank spaces, whereby a plurality of completed time tables may be compared.

2. A time table mechanism having a laterally moving principal time strip provided with a plurality of time indications forming vertical schedule columns extending transversely of said strip, the said strip having blank spaces extending transversely thereof 90 between said columns, a plurality of vertically moving strips having station names thereon, said strips moving parallel to each other and across the blank spaces of the principal strip, whereby a plurality of completed time tables may be made up side by side for comparison, and means for adjusting the said strips whereby relative changes in time tables may be made apparent.

3. A time table mechanism having a principal transversely movable time strip, an auxiliary transversely movable day and number strip adapted to form a continuation of the time tables to be shown, the said strips having vertical columns of indications thereon and blank spaces between said columns, arranged in alignment with each other, vertically movable station strips adapted to extend across the blank spaces of the principal strip, and auxiliary vertically movable strips, adapted to extend across the blank spaces of the auxiliary transverse strip, and in alignment with the said station strips and having data upon the face thereof for completing time table information, the structure being such that a plurality of completed time tables may be formed side by side for comparison.

4. A time table mechanism having a plurality of laterally moving time table strips 105 arranged parallel and forming extensions one of the other, a plurality of transversely movable vertically arranged indication strips arranged in alignment, the aligned strips thereof extending parallel to each other across said laterally moving time table strips whereby a plurality of completed time tables may be constructed, in position for comparison, and a housing having a front wall with openings therein 110

adapted to permit only those portions of the strips behind, to show through, which are required for the particular time tables being compared.

- 5 3. A time table mechanism comprising an inclosing housing, a time scroll having columns of time indications forming schedules thereon, said columns being spaced apart on the scroll, station strips adapted to 10 move across the time scroll so as to be brought in the spaces between the time indications, said station strips having columns of station names adapted to be brought opposite their respective indications upon the 15 time scroll, the structure being such that different pairs of time indication columns may be brought opposite different pairs of station name columns, to complete time table schedules for comparison.
- 20 4. A time table mechanism comprising a transversely movable time strip having time indications thereon forming separated schedule columns, rollers for carrying and moving said strips, auxiliary class and 25 number strips adapted to form continuations of the time tables to be presented, independently operable rollers carrying and moving said strips, aligned station and data strips extending transversely of the time 30 strips and auxiliary strips respectively, and independently operable rollers for adjusting and carrying the said station and data strips, the structure being such that new and old time table strips may be constructed 35 side by side for comparing the results of changes made therein.
7. A time table mechanism having a time strip carrying groups of time indications forming separate schedules, station strips 40 carrying groups of station names movable across said time strip for bringing the station names opposite the proper time indications, a housing having spaced openings therein for disclosing the data upon said 45 strips for a comparison of the schedules, means for indicating the schedules as being old or new, and adjustable indicators upon the housing adapted to show the points of change from one schedule to another, whereby 50 by effective parts of old and new schedules may be compared.
8. A time table mechanism having transversely movable time table forming strips of translucent material having opaque indications thereon adapted to form portions 55 of time tables, vertically movable translucent strips adapted to move across the face of the first mentioned strips, and having opaque indications thereon giving station 60 names and other data adapted to form portions of said time tables, a housing having openings adapted to permit light to shine through only where the indications, to form the time tables, are to be presented, and 65 lighting means behind the translucent strips

for illuminating the said strips and showing the opaque indications thereon, the structure being such that the strips may be adjusted for completing illuminated time tables in position for comparison.

70

9. A time table mechanism having means therein carrying groups of schedule indications, a housing inclosing said means and provided with spaced openings in one of its walls for displaying data upon said 75 means necessary for a comparison of time tables, and means mounted upon the outer surface of said housing capable of covering some or all of said apertures for accomplishing the exposure of effective parts of 80 compared time tables.

80

10. A time table mechanism having coöperating scrolls provided with groups of time table indications thereon, forming schedules, a housing inclosing said scrolls 85 and having series of openings in the walls thereof for displaying parts of the scrolls carrying time table indications and curtains of different shapes mounted upon the said housing and adapted to cover certain openings therein for effecting a comparison of the operative parts of old and new time tables.

90

11. A time table mechanism comprising coöperating strips carrying groups of indications forming time tables, a housing inclosing said scrolls and having properly spaced apertures in its walls adapted to expose to view different groups of indications, curtains mounted at the bottom of 95 said housing and means for holding said curtains so as to cover some or all of the columns of openings in the housing, whereby effective portions of old and new time tables 100 may be compared.

105

12. A time table mechanism comprising schedules made up of movable sections, arranged for relative comparison, some of said sections carrying station indications, pointers adjustably mounted adjacent to 110 said station indications and means for holding said pointers opposite any of the stations to indicate how far a train may move upon a given schedule.

110

13. A time table mechanism comprising 115 schedules arranged in proper relation to each other for comparison, means for holding said schedules in place, adjustable pointers arranged to be moved with respect to each schedule for indicating that the portion beyond one pointer is completed by the portion beyond the other pointer, rods for carrying said pointers and means for clamping the said pointers at any desired position upon said rods.

120

14. A time table mechanism comprising 125 adjustable schedules giving essential time table indications and arranged for comparison, a housing inclosing said schedules and provided with openings through which the 130

125

schedule indications may show forth, adjustable curtains mounted upon said housing and capable of being drawn over the schedules to show changes from old to new ones, and means for securing the curtains in their adjusted positions.

15. A time table mechanism comprising a housing, schedules mounted in said housing, curtains mounted at the upper part of said housing and capable of being drawn downwardly over portions of the schedules, and curtains mounted near the bottom of the housing and capable of being drawn upwardly over the said schedules, the structure being such that ineffective parts of schedules may be temporarily hidden from view.

16. A time table mechanism comprising a housing, time table schedules mounted therein, curtains of varying widths and shapes mounted on said housing and capable of covering portions of the schedules either longitudinally or transversely of the same, spring actuated rollers carrying said curtains and

detents projecting from the said housing 25 and adapted to engage the said curtains for holding the latter in adjusted positions.

17. A time table mechanism comprising schedules giving time table indications, a series of superposed curtains arranged adjacent to the schedules and capable of being drawn over the same, some of said curtains being made the full width of the schedule, others being made narrower for covering a portion of the said schedules, while others 35 are made narrow for a portion of their length and wider for the remainder of their length whereby a part of a time table may be arranged to follow a part of another time table at any given point or the relative hours 40 and minutes on the table may be changed.

In testimony whereof, I have hereunto set my hand, in presence of two witnesses.

WILLIAM NICHOLS.
